(57) **CLAIM**

The ornamental design for an organic light emitting diode device, as shown and described.

DESCRIPTION

FIG. 1 is a front view of an organic light emitting diode device showing our new design;

FIG. 2 is a rear view thereof;

FIG. 3 is a top view thereof;

FIG. 4 is a right side view thereof;

FIG. 5 is a cross-sectional view thereof taken along lines 5-5 shown in FIG. 1;

FIG. 6 is a cross-sectional view thereof taken along lines 6-6 shown in FIG. 1;

FIG. 7 is an enlarged cross-sectional view of an area thereof taken along lines 7-7 shown in FIG. 5; and,

FIG. 8 is an enlarged top view of an area thereof taken along lines 8-8 shown in FIG. 3.

A bottom view and a left side view of the organic light emitting diode device are omitted as they are symmetric in appearance to the top view of FIG. 3 and the right side view of FIG. 4, respectively.

The broken line showings of FIGS. 5-7 are environmental only and not part of the claimed design.
